SEWING MACHINE

Norman V. Christensen, Chicago, Harold J. Le Vesconte, Western Springs, George Sauer, Berwyn, and Oscar Quist, Chicago, Ill., assignors to Union Special Machine Company, Chicago, Ill., a corporation of Illinois

Application September 8, 1938, Serial No. 228,888

13 Claims.

(Cl. 112—165)

This invention relates to sewing machines; and it has reference more particularly to sewing machines of the kind disclosed in U. S. Patent No. 10,354, granted to S. C. Blodgett, on December 20, 1853, capable of making seams in which spaced needle thread loops passing through the fabric from opposite sides at opposed angles, are interlocked with each other at points of intersection at the fabric surfaces, the seam having the appearance of an ordinary lockstitch seam when viewed from either side of the fabric.

The chief aim of our invention is to extend the usefulness of sewing machines of the kind referred to with a view toward making possible their continuous operation at higher speeds for attainment of correspondingly greater output from them; insuring greater uniformity in the seams produced by them; and enabling production of seams anywhere within the area of the fabric being sewed as well as along its edges.

One way in which the foregoing and other important advantages may be readily realized in practice will appear from the following detailed description of the attached drawings, wherein Fig. I is a view, partly in front elevation and partly in longitudinal section, of a sewing machine conveniently embodying our invention.

Fig. II shows the machine in top plan with the top covers removed from its frame to expose important parts within.

Fig. III is a fragmentary view showing the machine in bottom plan.

Fig. IV is an end elevation of the machine.

Fig. V is a transverse sectional view taken as indicated by the arrows V—V in Figs. I and III.

Fig. VI is a fragmentary detail view looking as indicated by the arrows VI—VI in Fig. IV.

Figs. VII—XVIII are diagrammatic views showing the cycle of stitch formation with the coacting parts occupying different successive positions.

As herein illustrated, our improved sewing machine has an elongate horizontal rectangular work support 1 with a hollow standard 2 rising from one end thereof and supporting an integrally-formed longitudinal overhanging arm 3, which, at its free end, terminates in a hollow needle head 4. Confined to reciprocate axially in a plane inclined to the vertical is a needle bar 5 which is guided in aligned bearings 6 and 7 set respectively into the top and bottom of the hollow needle head 4, and which, at its lower end, carries a needle 8 adapted to penetrate fabric F' being sewed in the machine from above. The needle bar 5 is actuated, through a link 9, from a balanced crank member 10 at the left hand end

(Fig. I) of a horizontal shaft 11 journaled in fixed bearings 12, 13, 14 within the hollow of the overhanging arm 3.

Slidable axially in inset bushings 15 and 16 on the needle head 4 in parallel relation with the needle bar 5 is a presser bar 17 with a shank member 18 at its lower end whereto a presser foot 19 is pivotally connected, see Fig. IV. The presser foot 19 is maintained in yielding engagement with the fabric F by a helical spring 20 which surrounds the presser bar 17 and which is in compression between the bushing 15 and a fixed collar 21 on said bar within the hollow of the head 4. The bushing 15 is threaded into the top of the needle head 4 so that it may be adjusted axially to regulate the pressure of the spring 20. The collar 21 has a lateral projection 21a which extends outward through a vertical guide slot 22 in one side of the needle head 4 and so prevents rotation of the presser bar 17. By means of a vertical link 23, the collar 21 is coupled with one end of a lever 24 fulcrumed near its center on a screw stud 25 projecting laterally from the overhanging arm 3, see Figs. I and II. To the opposite end of the lever 24 is connected a drop link rod 26 (Figs. I and IV) which may extend to a foot treadle or knee press (not illustrated) and which, upon being actuated, will cause the presser bar 17 to be lifted in opposition to the spring 20 to facilitate introduction of the fabric F initially beneath the presser foot 19. A spring shown at 27 in Figs. I and IV serves to maintain the lever 24 normally in the position illustrated; and a cam finger indicated at 28 in Figs. IV and VI is provided as an auxiliary means for lifting the presser bar 17 and at the same time locking it in raised position when desired or required.

Cooperating with the needle 8 in the sewing is 40 a needle 29 which is adapted to penetrate the fabric F upwardly from below. As shown in Fig. IV, the needle 29 is secured to the upper end of a bar 30 which is oppositely inclined with respect to the bar 5 carrying the upper needle 8, so that it intersects the path of said upper needle at a point P in the top surface of the work support 1 in entering the fabric. The needle bar 30 is confined to endwise reciprocation in spaced guide bosses 31a, 31b on a plate-like carrier 31 which 45 is fulcrumed to oscillate about a stud 32 secured in one of a series of holes 33 in an underslung bracket 35 integrally formed with the work support 1 at the left hand end thereof. The lower needle bar 30 is connected by a link 36, with 50 one arm 37a of a bell crank 37 free on a rock

shaft 38 which is journaled at one end in the bracket 35, and at the other end in a bearing lug 39 pendant from the work support 1. To the other arm 37b of the bell crank 37 is connected the rod 40a of a strap 40 which embraces an actuating eccentric 41 on a horizontal shaft 42 extending longitudinally of the machine beneath the work support 1, see Fig. I. At the left hand end of the machine, the shaft 42 is journaled in another pendant bearing lug 43 on the work support 1, and at the right hand end extends through bearings 45, 46 in a downward prolongation 47 of the standard 2, below the work support 1, said prolongation being closed at the bottom by a removable cover plate 48 to serve as a sump which is kept filled with lubricating oil to the level conventionally indicated in Fig. I.

The fabric F is advanced crosswise of the work support 1 by a toothed four-motion feed dog 50 (Fig. V) which operates upwardly through an opening 51 in the throat plate 52 of the machine. As shown in Fig. V, the feed dog 50 overreaches the shaft 42 and has its shank secured by a screw 53 to a feed bar 55. At its rear end, the feed bar 55 is pivotally connected to the top of a vertical arm 56 on a rock shaft 57 at the side of the machine opposite that occupied by the rock shaft 38. The rock shaft 57 is journaled at one end in the bracket 35, and at spaced intervals in pendant lugs 58, 59 of the bed plate 1, and to it is clamped a slotted arcuate arm 61. By means of a bolt 62 adjustable along the slot of the arm 61, one end of a link 63 is connected to said arm, the other end of said link being connected at 65 to the strap 66 of another eccentric 67 on the shaft 42, the pivot 65 being supported at the swing end of a lazy bar 68 swingable on a rod 69 whereof the opposite ends are fixed in the bearing lugs 58, 59. By the action of the eccentric 67, the shaft 57 is oscillated continuously with resultant impartation of feeding movements to the feed dog 50. The throw of the feed dog 50 may be varied by adjusting the bolt 62 along the arm 61 without attendant change in the timing of the feed movements since the pivotal connection 65 between the link 63 and the eccentric strap 66 is restricted to a fixed arcuate path by the lazy bar 68. The arcuate arm 61 has its center of curvature in the axis of the pivot pin 65 which constitutes the common connection between the eccentric strap 66 and the links 63 and 68 at the time when the feed dog 50 is in its forward position, i. e., in its extreme position to the right in Fig. V. The necessary lift movements are induced in the feed dog 50 from still another eccentric 70 on the shaft 42, said eccentric being embraced by a strap 71 which is pivotally connected at its lower end at 72 to an underreaching arm 55a integrally formed with the feed bar 55. By the arrangement just described, the feed dog 50 is actuated in a well known manner to positively advance the fabric step by step crosswise of the work support 1 while opposed by the reacting pressure of the presser foot 19 from above. For the purpose of moving the lower needle 29 laterally in synchronism with the feed movements of the feed dog immediately upon having entered the fabric, in accordance with our invention, we have provided mechanism for imparting oscillatory movements to the carrier 31. As shown, this mechanism includes a link 73 whereof the lower end is connected at 74 to the carrier 31, and the upper end at 75 to an arm 76 clamped to the rock shaft 38 previously referred to. Similarly secured to the rock shaft 38

is another arm 77 which at 78 is connected to the lower end of the strap rod 79 of another eccentric 80 (Fig. III) on the shaft 42.

The shafts 11 and 42 are connected for rotation in unison by a transmission 81 within the hollow of the standard 2. This transmission includes spur gears 82, 83 respectively on the shafts 11, 42, and an intermediate intermeshing idler gear 85 which is free to rotate on a shaft 86 secured in bosses 87, 88 at opposite sides of the standard 2. As shown, the pinions 82, 83 comprise opposingly arranged half sections 82a, 82b, and 83a, 83b respectively which are rotatively adjustable relatively on the shafts 11 and 42 for wear take up. The transmission 81 per se, constitutes the subject matter of a co-pending application No. 211,712, filed on June 4, 1938, by George Sauer, one of the present applicants. While either of the shafts 11, 42 may be utilized as the drive shaft of the machine, we preferably employ the lower shaft 42 for that purpose, and to this end have provided it with a combined hand wheel and pulley 29. For convenience of operating the machine manually in making adjustments we have secured a hand wheel 90 to the upper shaft 11, as shown in Fig. I.

Pivotally connected at 91 to a fixed bracket 92 beneath the work support 1 is a finger 93 which is adapted to engage and temporarily hold the thread loops thrown out by the upper needle 8 as the latter begins to recede upwardly after having penetrated the fabric F, see Fig. IV, so that the lower needle 29 may enter said loops before it has penetrated the fabric. As shown, the finger 93 has a depending arm 95, which, by means of a link 96 is coupled with an arm 97 on a rock shaft 98 journaled on the brackets 35 and 39 immediately above the shaft 38. Oscillatory movements are imparted to the shaft 98 to actuate the loop-engaging finger 93 in a manner more fully explained presently, from an eccentric 99 on the shaft 42 whereof the strap rod 100 is coupled to another arm 101 secured to said shaft 98, see Figs. III and V. Pivoted at 102 to a lateral projection 103 on the shank member 18 to which the presser foot 19 is pivoted is a finger 105 which is adapted to engage the thread loop thrown out by the lower needle 29 as the latter begins to recede downward, after having penetrated the fabric F, so that the upper needle 8 may enter said loops at the initiation of its down strokes. The arm 106 of the finger 105 is coupled, by means of a horizontal link rod 107 with the lower end of an arm 108 clamped to one end of a rock shaft 109, which, as shown in Fig. VI, is journaled in a lug projection 110 at the rear side of the needle head 4. To the opposite end of the rock shaft 109 inward of the lug 110 is secured an upwardly extending arm 111, which, at the top, has a pivotal connection at 112 with the strap rod 113 of the eccentric 114 on the upper needle actuating shaft 11—all as shown in Fig. IV.

The arrangement and setting of the various parts of the machine mechanism in the manner described results in the performance of a continuously repeating stitch-forming cycle which is as follows:

In Fig. VII, the lower needle 29 is passing upward through the thread loop (not shown) of the upper needle 8 held by the finger 93 and about to enter the fabric F from beneath. In Fig. VIII, the lower needle 29 has just penetrated the fabric F and is beginning to move laterally to the left concurrently with its axial

advancement upwardly as the feed dog begins feeding the fabric in the same direction. At the same time the finger 93 is receding to release the thread loop of the upper needle 8 and the finger 105 is advancing in preparation for engaging the thread loop (not shown) of said lower needle. The several parts continue in these movements through the positions of Fig. IX to the positions of Fig. X where the lower needle 29 has fully penetrated the fabric F and reached its highest position. In Fig. XI, the lower needle 29 has just begun to recede downward axially while still continuing in its leftward movement synchronously with advance of the fabric F. In Fig. XII, the finger 105 has entered the thread loop of the receding lower needle 29. In Fig. XIII, the lower needle 29 has completed its leftward movement and is receding out of the fabric; while the upper needle 8 is passing down through the loop of the lower needle thread held by the finger 105 which is now in its fully advanced position. Fig. XIV shows the upper needle 8 entering the fabric with the lower needle 29 beginning its return move laterally to the right, and the finger 93 beginning to advance toward its active position. The parts thereafter continue in these movements through the positions of Fig. XV to the positions of Fig. XVI wherein the upper needle 8 has completed its downward stroke. In Fig. XVII the upper needle 8 has begun its upward stroke and the finger 93 is about to engage the thread loop of said needle. In Fig. XVIII, the upper needle 8 is about to leave the fabric and the finger 93 is holding the upper needle thread loop in readiness for the lower needle 29 to pass through it in the manner shown in Fig. VII.

Repetitions of the above cycle will obviously result in a seam like that shown in the Blodgett patent hereinbefore referred to. It will moreover be evident from the foregoing that our improved sewing machine is susceptible of continuous operation at speeds comparable with that of ordinary single needle sewing machines, and moreover that it is not limited to seaming solely along the edges of the fabric as is the case with the machine of the Blodgett patent supra.

The length of stitch may be varied by selection between the holes 33 in the bracket 35 for placement of the stud 32 on which the carrier 31 for the lower needle 29 oscillates, since said holes are arranged in an arc struck from the point P (Figs. IV and VII) at the surface of the work support of the machine in which the axial fabric-penetrating paths of the needles 8 and 29 intersect. Thus, when the stud 32 is shifted to the right in Fig. IV, the angle between the link 73 and the arm 76 will be decreased with attendant decrease in the amount of rocking movement imparted to the carrier 31. Similarly, shifting the fulcrum stud 32 leftward in Fig. IV will be attended by increase in the angle between the link 73 and the arm 76, and hence in the rocking movement of the lower needle carrier 31. After the desired throw of the carrier 31 is determined, the feed stroke of the feed dog 50 is correspondingly changed by adjusting the position of the eccentric 67 on the shaft 42. Notwithstanding changes in the position of the fulcrum pin 32 for the lower needle guide member 31, the path of the lower needle 29 will intersect the path of the upper needle 8 substantially at the point P at the surface of the throat plate 52, since the arc containing the holes 33 for said pin is struck from

said point. Accordingly the lateral feed movement of the lower needle 29 will under all conditions of adjustment of the fulcrum 32 start substantially at the point P and the increases or decreases in movement resulting from such adjustments will be at the end of the feed stroke of said needle. In the event that extreme accuracy is required to insure intersection of the lower needle 29 with the upper needle 8 exactly at the point P, the arm 76 may be adjusted circumferentially of the rock shaft 38 to the necessary extent after transposal of the fulcrum pin 32 for the guide member 31, in a manner which will be obvious from Fig. IV.

Having thus described our invention, we claim:

1. A sewing machine comprising a work support; feeding means for engaging fabric and intermittently advancing it on the work support; a needle adapted to penetrate fabric on the work support from above; means for actuating said needle; a second needle adapted to penetrate the fabric from below; a pivoted carrier in which the second needle is guided for axial movement; means for actuating the second needle in alternation with the first needle; and means for oscillating the carrier while the second needle is engaged in the fabric, to move said needle laterally in synchronism with the fabric advancing movements of the feeding means.

2. A sewing machine comprising a work support; feeding means for engaging fabric and intermittently advancing it on the work support; a needle adapted to penetrate fabric on the work support from above; means for actuating said needle; a second needle adapted to penetrate the fabric from below; a pivoted carrier in which the second needle is guided for endwise reciprocation; a shaft journaled beneath the work support; means deriving movement from said shaft for reciprocating the second needle endwise as aforesaid in alternation with the movements of the upper needle; and means also deriving movement from the shaft for actuating the carrier to move the second needle laterally while it is engaged in the fabric synchronously with the fabric advancing movements of the feeding means.

3. A sewing machine comprising a work support; feeding means for engaging the fabric and intermittently advancing it on the work support; a needle adapted to penetrate the fabric from above; a shaft above the work support from which said needle is actuated; a second needle adapted to penetrate the fabric from beneath; a shaft below the work support from which the second needle is actuated in alternation with the first needle; means also actuated from the lower shaft for moving the second needle laterally, while engaged in the fabric, in synchronism with the fabric advancing movements of the feeding means; means below the work support actuated from the lower shaft for spreading and temporarily holding the thread loop of the first needle to enable entry thereinto of the second needle; means above the work support actuated from the upper shaft for spreading and temporarily holding the thread loop of the second needle to enable entry thereinto of the first needle; and transmission means interconnecting the two shafts.

4. A sewing machine comprising a work support; adjustable feeding means for engaging the fabric and intermittently advancing it on the work support; a needle for penetrating the fabric from above; means for actuating the needle; a

second needle for penetrating the fabric from beneath; means for actuating the second needle; a pivoted carrier below the work support in which the second needle is guided for reciprocation in an inclined path intersecting that of the first needle in a point at the surface of the work support; mechanism for oscillating the carrier to move the second needle laterally while in the fabric, in synchronism with the fabric advancing movements of the feeding means, said mechanism including a rock shaft below the work support, a lateral arm on said rock shaft and a vertical link connecting said arm with said carrier; means whereby the pivot for the carrier can be adjusted along an arc struck from the point of intersection of the needle paths, to increase or decrease the lateral movements of the second needle compensatively with the adjustments of the feeding means.

5. A sewing machine comprising a work support; a feeding element for intermittently advancing the fabric on the work support; means for actuating the feeding element; a pair of needles for penetrating the work from opposite sides; guides respectively determining passage of the needles through a point of intersection at the level of the work support; means for actuating the needles; means for actuating one of the guides so that the corresponding needle is shifted laterally relative to said point while in the fabric synchronously with the advance shifts of the fabric by the feeding means; and means for adjusting the feed actuating means and the guide of the laterally shiftable needle compensatively without entailing any substantial change in the position of the intersection point for the purpose of stitch length variation relative to said point.

6. A sewing machine comprising a work support; a feeding element for engaging fabric and intermittently advancing it on the work support; means for actuating said feeding element; a pair of needles adapted to alternately penetrate the fabric from opposite sides respectively; means for guiding the needles to reciprocate axially along angular paths which intersect in a point at the surface of the work support; means for actuating the needles; means for moving the guide for one of the needles so that the path of said needle is shifted laterally, relative to the aforesaid point after the needle has entered the fabric, in synchronism with the advance shifts of the fabric by the feeding element; and means for adjusting the feed actuating means and the guide of the laterally shiftable needle compensatively to effect stitch length variation substantially without attendant change in the point of intersection of the needle paths.

7. A sewing machine comprising a work support; a feeding element for engaging fabric and intermittently advancing it on the work support; means for actuating said feeding element; a pair of needles adapted to alternately penetrate the fabric from opposite sides respectively; guides respectively for said needles determining intersection of the paths of the latter in a fixed point at the level of the work support; means for actuating the needles; actuating means for moving one of the guides to laterally shift the path of the corresponding needle while in the fabric synchronously with the advance shifts of the fabric by the feeding element; means at one side of the work support for spreading and temporarily holding the thread loop of one needle to enable entry thereinto of the other needle after the latter has penetrated the fabric; means at the opposite

side of the work support for spreading and temporarily holding the thread loop of said other needle to enable entry thereinto of the first mentioned needle after the latter has penetrated the fabric; and means for adjusting the feed actuating means and the guide of the laterally shiftable needle compensatively to effect stitch length variation substantially without attendant change in the point of intersection of the needle paths.

8. A sewing machine comprising a work support; a feeding element for engaging fabric and intermittently advancing it on the work support; means for actuating said feeding element; a pair of needles adapted to alternately penetrate the fabric from opposite sides respectively; means for actuating the needles; guides respectively for the needles to determine intersection of the paths of the latter in a point at the level of the work support; means for moving one of the guides to laterally shift the path of the corresponding needle after it has entered the fabric, in synchronism with the advance shifts of the fabric by the feeding element; means at one side of the work support for spreading and temporarily holding the thread loop of one needle to enable entry thereinto of the other needle after the latter has penetrated the fabric; means at the opposite side of the work support for spreading and temporarily holding the thread loop of said other needle to enable entry thereinto of the first mentioned needle after the latter has penetrated the fabric; and means for adjusting the feed actuating means and the guide of the laterally shiftable needle compensatively to effect stitch length variation substantially without attendant change in the point of intersection of the needle paths.

9. A sewing machine comprising a horizontal work support; a feeding element for engaging fabric and intermittently advancing it on the work support; means for actuating the feeding element; a pair of opposing upper and lower needles adapted to alternately penetrate the fabric respectively from opposite sides; means for actuating the needles; guides for determining intersection of the paths of the needles in a point at the level of the work support; means below the work support for spreading and temporarily holding the loop of the upper needle after it has penetrated the fabric to permit entry of the lower needle; means above the work support for similarly spreading and temporarily holding the loop of the lower needle after it has penetrated the fabric to permit entry of the upper needle; actuating means operative to move the guide of one of the needles while engaged in the fabric to laterally shift its path synchronously with each fabric-advancing shift of the feeding element; and means for adjusting the actuating feed means and the guide of the laterally shiftable needle compensatively to effect stitch length variation substantially without attendant change in the point of intersection of the needle paths.

10. A sewing machine comprising a horizontal work support; a shaft journaled above said work support; another shaft journaled below the work support; a feeding element for engaging fabric and intermittently advancing it on the work support; means for actuating the feeding element; a needle adapted to penetrate the fabric from above; means for guiding the needle to pass through the work support; means whereby said needle is actuated from the upper shaft; a second needle adapted to penetrate the fabric from below; means whereby the second needle is actuated from the lower shaft in alternation with the

first needle; means for guiding the second needle in a path which intersects the path of the first needle at the level of the work support; means actuated from the lower shaft whereby the guide means for the second needle is moved to laterally shift the path of the latter while engaged in the fabric in synchronism with each fabric-advancing shift of the feeding means; and means for adjusting the feed actuating means and the guide means of the laterally shiftable needle compensatively to effect stitch length variation substantially without attendant change in the point of intersection of the needle paths.

11. A sewing machine comprising a work support; a needle; means for reciprocating the needle endwise; means for guiding the needle to pass through the work support always at the same point during its work piercing stroke; means to cooperate with the needle in stitch formation at said point; means for moving the guide to shift the needle laterally after having penetrated the work to intermittently advance the work on the work support; and means for adjusting the guide for the purpose of increasing or decreasing the lateral throw of the needle in one direction with respect to the point aforesaid in which the needle passes through the work support, to vary the stitch length.

12. A sewing machine comprising a work support; a needle; means for reciprocating the needle endwise; a feeding element; means for reciprocating the feeding element to intermittently advance fabric on the work support; means for guiding the needle to pass through the work support always at the same point during its work penetrating stroke; means for moving the guide to shift the

needle laterally while in the fabric in synchronism with the feeding movement of the feeding element; means to cooperate with the needle in stitch formation at said point; means for adjusting the guide for the purpose of increasing or decreasing the lateral throw of the needle with respect to the point aforesaid in which the needle passes through the work support, to vary the stitch length; and means for adjusting the feed reciprocating means compensatively to correspondingly increase or decrease the throw of the feed dog relative to a fixed point of starting.

13. A sewing machine comprising a work support; a needle; means for reciprocating the needle endwise; a four motion feed dog; means for actuating the feed dog to intermittently advance fabric on the work support; means for guiding the needle to pass through the work support always at the same point during its work penetrating stroke; means for moving the guide to shift the needle laterally while in the fabric in synchronism with the feeding stroke of the feed dog; means to cooperate with the needle in stitch formation at said point; means for adjusting the guide for the purpose of increasing or decreasing the lateral throw of the needle with respect to the point aforesaid in which the needle passes through the work support to vary the stitch length; and means for adjusting the feed actuating means compensatively to correspondingly increase or decrease the stroke of the feed dog relative to a fixed point of starting.
